UNITED STATES PATENT OFFICE.

MICHAEL BESHOAR, OF TRINIDAD, COLORADO.

CROSSING-GUARD FOR RAILWAYS.

SPECIFICATION forming part of Letters Patent No. 374,772, dated December 13, 1887.

Application filed April 18, 1887. Serial No. 235,199. (No model.)

To all whom it may concern:

Be it known that I, MICHAEL BESHOAR, a citizen of the United States, and a resident of Trinidad, in the county of Las Animas and State of Colorado, have invented certain new and useful Improvements in Crossing-Guards for Railways; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a railway-crossing provided with my improved guard or gate. Fig. 2 is a top plan view of the same. Fig. 3 is a transverse vertical sectional view on line *xx*, Fig. 2; and Fig. 4 is a similar sectional view of one of the trenches and its

cover, taken on line *yy*, Fig. 2.

Similar numerals of reference indicate corresponding parts in all the figures.

My invention has relation to that class of gates or guards for railway-crossings or similar places in which bars or chains or ropes are stretched across the roadway at both sides of the track by winding the said chains or ropes upon a windlass; and it consists in the improved construction and combination of parts of such a gate or guard, as hereinafter more fully described and claimed.

In the accompanying drawings, the numeral 1 indicates an upright casing, which is secured at one side of the railway-track and at one side of the roadway, and three upright posts, 2, are secured in the three remaining corners of the intersecting roads. A windlass, 3, is journaled in the upper end of the casing and has its drum divided in three portions separated by suitable flanges, 4, and this windlass is provided with a suitable crank, 5, for revolving it, and with a ratchet-wheel, 6, engaged by a pawl, 7, for the purpose of holding the windlass when the guards are raised.

Two ropes or chains, 8 and 9, are secured to two of the sections of the drum and wind upon the same, one, 8, passing out through an aperture, 10, in the upper end of the casing and being secured at the other end to the post at the opposite side of the roadway, having, preferably, a bar, 11, forming a part of it, the said bar spanning the roadway when

raised. The other rope or chain, 9, passes from the windlass down through the casing and under a pulley, 12, in the lower end of the same, 55 whereupon it passes under the track in a suitable trench, 13, and at the other side of the track the rope or chain passes under a pulley, 15, and up through the post at that side and over a pulley, 16, in the upper end of the post. 60 This chain or rope is likewise preferably provided with a bar, 17, forming a part of it, and the other end of the chain at the end of the bar is secured to the post at the farther side of the roadway. It will thus be seen that 65 when the windlass is revolved, winding the ropes or chains upon the drum-sections, the said ropes or chains and their bars will be raised from the ground and stretched across the roadway, stopping the passage across the 70 track.

A third rope or chain, 18, is secured to the third drum-section of the windlass, and is wound in the opposite direction to the other ropes or chains, and this rope or chain passes 75 under a pulley, 19, at the lower end of the upright casing and over a pulley, 20, in the transverse trench, having its end secured to the rope or chain passing in the trench; and it will be seen that when the ropes or chains are 80 unwound from the windlass this third rope or chain will be wound upon the windlass and drag the rope or chain back in the trench, so that the portion of the rope or chain spanning the roadway and its bar may drop by their own gravity without having to drag the portion of the 85 chain or rope in the trench.

Trenches 21 pass across the roadway at both sides of the track parallel with the same between the upright posts, and these trenches 90 may be suitably lined with wood or iron or other material, and covers 22 are hinged in the rabbeted edges of the trenches nearest to the track and may cover the trenches and have their upper surfaces flush with the roadway, resting with their edges in the rabbeted edges 23 of the trenches. These covers are provided with rods 24 near their ends, projecting from the free edges of their upper surfaces, and the hinge-edges of the covers are 95 preferably provided with boards or series of arms, 26, at right angles to the under-sides of the covers.

It will be seen that when the ropes or chains

are wound upon the windlass and stretched across the roadway the bars in the chains will raise the covers and bear against the rods of the covers, keeping them upright while the 5 chains are stretched, and when the chains or ropes are slackened and lowered the covers and arms will tilt back again, dropping over the trenches, the weight of the chain or rope or bar falling upon the board or series of arms 10 at the hinge-edge of each cover, serving to depress the said board or series of arms and to thus tilt the cover over the trench. In this manner the ropes or chains and their bars may be covered and protected when lowered, and 15 the covers and their rods will serve to form parts of the guards or gates, together with the chains or ropes and their bars.

If desired, the pulleys and the drum-sections may be replaced by sprocket-wheels when 20 chains are used in the guard, the ends of the chains hanging down loose in that case instead of being secured to the drum-sections, and numerous modifications in the construction of details of the device may be made 25 without departing from the spirit of my invention.

Having thus described my invention, I claim and desire to secure by Letters Patent of the United States—

30 1. In a guard or gate for railway-crossings, the combination of an upright casing having a windlass journaled in its upper end and provided with a crank and ratchet-wheel and pawl and having guide-pulleys journaled at 35 its lower end, an upright at the opposite side of the track having guide-pulleys at its upper and lower ends, uprights at the opposite sides of the roadway, a rope or chain secured to the

windlass and winding upon the same and secured at its other end to the opposite upright, 40 a rope or chain passing under the guide-pulley in the lower end of the casing and under the track and up through the other upright over its upper guide-pulley to the upright opposite to the upright with the pulleys, and a 45 rope or chain secured to the windlass and winding upon it in the opposite direction to the two ropes or chains and passing under a guide-pulley at the foot of the casing and over a guide-pulley in the trench under the track, 50 having its ends secured to the rope or chain passing under the said pulley in the trench, as and for the purpose shown and set forth.

2. In a guard or gate for railway-crossings, the combination of a chain, rope, or bar across 55 the roadway, having means for raising and lowering it, a trench for the reception of the lowered rope, chain, or bar, having rabbeted edges, and a cover hinged to the edge of the trench nearest the track and resting in the 60 rabbeted edges and formed with outwardly-projecting rods near its ends projecting beyond the free edge and with a board or series of arms projecting at a right angle to the cover at the hinge-edge and upon its under side for 65 the bar or rope or chain to bear against when lowered, as and for the purpose shown and set forth.

In testimony that I claim the foregoing as my own I have hereunto affixed my signature in 70 presence of two witnesses.

MICHAEL BESHOAR.
